UNITED STATES PATENT OFFICE.

HARRY W. BRYCE, OF DOWNS GROVE, ILLINOIS, ASSIGNEE TO KELLOGG SWITCH-BOARD AND SUPPLY COMPANY, OF CHICAGO, ILLINOIS, A CORPORATION OF ILLINOIS.

TELEPHONE SYSTEM.

1,354,020.

Specification of Letters Patent. Patented Sept. 28, 1920.

Application filed October 6, 1915. Serial No. 54,293.

To all whom it may concern:

Be it known that I, HARRY W. BRYCE, a citizen of the United States of America, residing in Downers Grove, in DuPage county and State of Illinois, have invented certain new and useful Improvements in Telephone Systems, of which the following is a specification.

My invention relates to telephone systems and has to do more particularly with manually operated link and trunk circuits which are employed for interconnecting telephone lines.

One of the features of my invention is the provision of a link circuit that is provided with so-called automatic ringing apparatus, the operation of which is initiated by the insertion of the calling plug of the link circuit into the multiple jack of a called subscriber's line and in which the said apparatus is rendered ineffective upon the insertion of the said calling plug into a trunk jack connected to a trunk circuit. Another feature of my invention is the novel means of controlling the calling supervisory signal of the link circuit when it is used in conjunction with a trunk circuit to extend a connection to a distant telephone exchange. Another feature of my invention is the novel means of controlling the supervisory apparatus of the trunk circuit and the novel means of controlling the apparatus, associated with the outgoing end of the trunk circuit, from the incoming end. These and other features will be more particularly pointed out in the ensuing specification and the appended claims.

Referring to the accompanying drawing, the system there illustrated includes two substations A and B, which terminate in line circuits L and L¹ at different exchanges. The cord circuit C which is at the same exchange with the line circuit of substation A is adapted for interconnecting lines terminating in its exchange or for extending connections to trunks leading to distant exchanges. The trunk circuit D, of which the outgoing end is located in the same exchange with the line of substation B, is connected to the trunk jack TJ in the exchange of substation A. The line circuit L associated with the substation A comprises a double wound line relay LR, a cut-off relay CO, a line signal LS, and multiple jacks J, which

in practice, appear before different operators' positions at the switchboard.

The operator's cord circuit C includes an answering plug AP for connecting to calling subscribers' lines and a calling plug CP for connecting to called subscribers' lines or to trunk circuits terminating in distant exchanges. Associated with the answering plug AP is an answering tip supervisory relay AT and an answering sleeve supervisory relay AS, the latter relay operating to connect the operator's telephone O with the calling subscriber's line when the plug AP is connected to a calling subscriber's line. The relays AS and AT together control the calling supervisory lamp AL. Associated with the calling plug CP is a calling tip supervisory relay CT and a calling sleeve supervisory relay CS, the two relays co-operating to control the circuit of the calling supervisory lamp CL. I provide automatic ringing which is initiated upon connection of the calling plug CP to the jack of the called subscriber's line, but which is rendered ineffective when the calling plug CP is connected to a trunk jack TJ. I also provide a ringing control relay RC, an interrupter relay IR, and an interrupter I for controlling the automatic intermittent application of the ringing current from the generator G to the terminals of the called subscriber's line. The operator's control relay OC controls the disconnection of the operator's telephone from the link circuit C.

The trunk circuit D terminates at the first exchange in a trunk jack TJ and at the distant exchange in the trunk calling plug TCP. The trunk jacks TJ may be multipled to a plurality of operators' positions. Associated with the trunk jack TJ is the repeating coil R and the relays SC and SC¹, whose function will hereinafter appear. Associated with the incoming end of the trunk D at the distant exchange is a repeating coil R¹, a double wound relay 2 provided with a comparatively high resistance winding 8 and a comparatively low resistance winding 9, and a control relay CR for controlling the circuit of the supervisory lamp SL. Associated with the trunk calling plug TCP is the calling sleeve supervisory relay AS¹ and a calling tip relay CT¹. I provide a party line ringing key RK for associating the desired ringing cur-

rent generator with the trunk circuit D for signaling the desired substation upon a party line. I also provide a ringing control relay RCR, an interrupter I^1 , and an 5 interrupter relay IR^1 for controlling and for intermittently providing ringing current from the desired generator to the called subscriber's line. The line circuit L^1 associated with the substations B, B^1 , B^2 and B^3 10 only trunks of B^1 , B^2 and B^3 being shown) comprise a double wound cut-off relay CO^1 , a line relay LR^1 for controlling the line signal LS^1 and a plurality of jacks J^2 .

Having described in general the apparatus used in the system illustrated, the operation of said system for connecting two subscribers in different exchanges and for connecting two subscribers in the same exchange, will now be described.

- 20 Assuming the subscriber at substation A desires connection with the subscriber at substation B, whose line terminates at a distant exchange, he first removes his receiver from its switch-hook thereby establishing a 25 circuit through the line relay LR^1 . The line relay upon energizing, closes a circuit through the line signal lamp LS^1 to notify the operator that a connection is desired. The operator in response to the said signal 30 inserts the answering plug AP of the cord circuit C into the jack J, thereby establishing a series energizing circuit for the cut-off relay CO^1 and the answering sleeve supervisory relay AS. The said relays are therefore 35 energized, the relay CO^1 disconnecting the line relay LR^1 from the subscriber's line, thus extinguishing the line signal LS^1 , and the answering sleeve relay AS connecting the operator's telephone O through its alternate contacts 5 and 6 to the line of the calling subscriber. The answering tip relay AT is also energized upon the insertion of the 40 answering plug AP into the jack J and upon energizing prevents a premature lighting of the answering supervisory lamp AL. The operator, upon learning that the subscriber at substation B is desired, whose line terminates in a distant exchange, presses the orderwire key OK leading to the said exchange, in which the line of substation B 45 terminates and inquires of the distant operator which trunk is to be used for the connection. The operator at the first exchange having been assigned to the trunk D inserts the calling plug CP into the trunk 50 jack TJ.

Responsive to the connection of the plug CP to the trunk jack TJ, a series circuit is closed through the supervisory control relay SC^1 , and the calling sleeve relay CS and operator's control relay OC in multiple, 60 traced from ground through the said relay SC^1 , sleeve contact of the trunk jack TJ and calling plug CP, and through the said calling 65 sleeve relay CS and control relay OC to

battery. The resistance of relay SC^1 is such that it does not permit sufficient current to flow through the relay CS to cause it to operatively energize. However, the relays SC^1 and OC energize in series, the former 70 relay closing a circuit through the relay SC, associated with the trunk jack TJ, and through the high resistance winding 8 of the relay 2 associated with the repeating coil R^1 , the latter relay disconnecting the 75 operator's set from the strands of the link circuit C at its alternate contacts 70 and 71. The circuit for relay 2 may be traced from ground through the said high resistance winding 8 of relay 2, over a simplex circuit including the windings 10 and 11 of the repeating coil R^1 in multiple and windings 12 and 13 of the repeating coil R in multiple, alternate contact 14 of relay SC^1 and through the said relay SC to battery. 80 The resistance of the winding 8 of relay 2 is such as to prevent a sufficient flow of current to operatively energize relay SC. However, relay 2 energizes at this time and closes a circuit through the supervisory lamps SL^1 and SL^2 . The circuit for supervisory lamp SL^1 extends from ground through alternate contact 16 of relay 2, normal contact 17 of relay CR and through the said supervisory lamp SL^1 to battery. The circuit for supervisory lamp SL^2 extends from the same ground through alternate contact 16 of relay 2, normal contact 18 of relay CR, normal contact 37 of relay 35 and through the supervisory lamp SL^2 to battery. 90

The operator at the distant exchange after receiving the number of the called subscriber from the subscriber's operator, tests the line of the called subscriber and assuming the said line to be idle she inserts the 10 trunk calling plug TCP of the trunk circuit D into the jack J^2 of the called subscriber's line and presses a ringing button of key RK to select and connect the desired frequency to operate the call bell at 11 the called subscriber's substation. Upon the operation of the ringing button a circuit is closed through the ringing control relay RCR extending from ground through the contact of the operated button and through the 12 said ringing control relay RCR to battery. The ringing control relay RCR, upon energizing, closes a locking circuit for itself, traced from ground through alternate contact 16 of relay 2, normal contact 20 of relay AS^1 , alternate contact 22 of said relay RCR and through its winding to battery. A further result due to the energization of the ringing control relay RCR is the closure of a circuit through the calling tip relay CT^1 , traced from ground through the upper winding of the cut-off relay CO^1 , the tip contacts of the jack J^2 and trunk calling plug TCP, alternate contact 26 of relay RCR and through the winding of said relay 13

CT¹ to battery. The relay CO¹, upon energizing, disconnects the line relay LR¹ and connects the ring and sleeve conductors of the jack J² together at its alternate contact 27, the two contacts engaging the sleeve contact of the plug TCP. The calling tip relay CT¹ upon energizing, closes a locking circuit for itself through its alternate contact 28 to ground at cutoff relay CO¹ and disconnects the test conductor leading to the operator's telephone O¹, connects the tip strand of the trunk circuit T to the winding 29 of the repeating coil R¹, and closes a circuit through relay CR to battery. The said relay CR, upon energizing, opens the circuit of lamp SL at its contact 17 and closes a substitute circuit for the supervisory lamp SL¹ traced from ground through its alternate contact 18, normal contact 37 of relay 20, through the said lamp to battery. The circuit for the interrupter relay IR¹, which is closed upon the energization of the ringing control relay RCR, extends from ground through the lower winding of said relay, alternate contact 32 of relay RCR, through the interrupter I¹ to battery. The interrupter relay upon energizing applies ringing current from the selected generator to the terminals of the called line, the path for the ringing current being traced from the selected generator through the ringing key contacts, alternate contact 33 of relay 2, alternate contact 34 of relay IR¹, sleeve conductor of the trunk calling plug TCP, ring and sleeve conductors of the jack J², through the called substation, back through the tip conductor of jack J², and plug TCP, alternate contact 25 of relay IR¹ and through its non-inductive winding to battery.

Upon the response of the called subscriber at substation B, a circuit is closed through the answering sleeve supervisory relay AS¹ traced from battery through the said relay, normal contact 34 of relay IR¹, sleeve contact of plug TCP, ring and sleeve contacts of jack J², through the called subscriber's substation and through the upper winding of relay CO¹ to ground. The answering sleeve supervisory relay AS¹, upon energizing, closes a circuit through relay 35, traced from battery through the said relay and through the alternate contact 36 of relay AS¹ to ground. The relay 35, upon energizing, closes a locking circuit for itself through its alternate contact 37 and also extinguishes the supervisory lamp SL¹, thus notifying the trunk operator that the called subscriber has responded. A further result due to the energization of relay AS¹ is the opening of the locking circuit for the ringing control relay RCR and the closing of a circuit through the winding 9 of relay 2 at its contact 20. The relay RCR, upon de-energizing, disconnects the interrupter I

from the interrupter relay IR¹ and opens the circuit of relay CT¹ at its contact 26, the relay CT¹ remaining energized, however, through its alternate contact 28. The closure of the circuit through winding 9 of relay 2 permits sufficient current to flow over the simplex circuit formed by the two conductors of the trunk circuit to permit relay SC, associated with the trunk jack TJ, to energize, the circuit extending from battery through the winding of said relay SC, alternate contact 14 of SC¹, simplex circuit formed by the two trunk conductors, winding 9 of relay 2, alternate contact 20 of relay AS¹ and alternate contact 16 of relay 2 to ground. Relay SC, upon energizing, closes its alternate contact 40 thereby closing a circuit for the calling tip supervisory relay CT of link circuit C through the impedance coil IC¹, the circuit extending from battery through the said coil IC¹, normal contact 41 of relay IR, ring contacts of plug CP and jack TJ, winding 42 of repeating coil R, alternate contact 40 of relay SC, winding 33 of repeating coil R, tip contacts of jack TJ and plug CP, normal contact 44 of relay IR and through the calling tip supervisory relay CT to ground. The relay CT upon energizing, effaces the calling lamp CL, thus notifying the operator at the link circuit C that the called subscriber has responded and prepares a circuit for the guard relay GR. A further result due to the energization of relay SC is the closure of an operating circuit for calling sleeve supervisory relay CS, traced from battery through the said relay CS, sleeve contacts of plug CP and jack TJ, through the resistance X and alternate contact 45 of relay SC to ground. The resistance X is such as to permit the calling supervisory sleeve relay CS to receive sufficient current to effectively energize. Relay CS, upon energizing, closes a circuit through the guard relay GR traced from battery through the winding of said relay GR, normal contact 46 of ringing control relay RC, alternate contact 47 of relay CT and through the alternate contact 48 of relay CS to ground. The guard relay, upon energizing, closes a locking circuit for itself through its alternate contacts 49 and opens the circuit of relay RC at its contact 50. The subscribers may now carry on an uninterrupted conversation over the heavily marked conductors.

Assuming now that the subscribers have finished conversation, the subscriber at substation A replaces his receiver upon its switch-hook opening the circuit of the answering tip supervisory relay AT of the cord circuit C thus permitting the relay to again close its normal contact 51 to thereby cause the supervisory lamp AL to glow. The subscriber at substation B, replacing

his receiver upon its switch-hook, opens the circuit of answering sleeve supervisory relay AS¹ at the switch-hook contacts. The relay AS¹ upon deenergizing, opens the circuit of relay 35 at its contact 36, and opens the operating circuit of relay SC at its contacts 20. Relay 35 upon deenergizing, closes a circuit for supervisory lamp SL¹ at its normal contact 37. Relay SC upon deenergizing, opens the circuit of the calling tip supervisory relay CT at its contact 40, thereby permitting the said relay to deenergize and close a circuit through the calling lamp CL at its normal contact 47. The relay CS, however, remains energized, it being so adjusted that after it once operatively energizes, it remains so, due to the current received through the relay SC¹.

The operator at the cord circuit C noting the two lighted supervisory signals withdraws the plugs AP and CP from their respective jacks J and TJ. The removal of the plug AP from its jack J permits the cut-off relay of line circuit L to deenergize and the answering sleeve supervisory relay AS to deenergize. The removal of the calling plug CP from the jack TJ permits the calling sleeve supervisory relay CS and the operator's control relay OC to deenergize. The relay CS, upon deenergizing, permits the guard relay GR to deenergize thereby placing the link circuit C in condition to again be used to establish connection between subscribers' lines. The removal of the calling plug CP from trunk jack TJ also permits the relay SC¹ to deenergize thereby opening the series circuit of the relays SC and 2 of the trunk circuit D. The trunk operator upon noting the glowing of the supervisory lamp removes the trunk calling plug TCP from jack J² thereby permitting the calling tip supervisory relay CT¹ to deenergize. The relay CT¹, upon deenergizing, opens the circuit of the control relay CR, thereby placing the apparatus of the trunk circuit D in condition to be used for extending further calls.

Assuming now that the calling subscriber A wishes connection with a second subscriber located at the same exchange, the call proceeds as hereinbefore described up to the point where the operator inserts the calling plug into the trunk jack TJ. In this instance the operator inserts the calling plug CP into a multiple jack J (similar to the jack J of the line circuit L) of the called subscriber's line. The insertion of the calling plug CP into the jack of the called subscriber's line closes an energizing circuit for the operator's control relay OC and the calling sleeve relay CS in multiple and through the cut-off relay of the called subscriber's line. The operator's control relay OC, upon energizing, disconnects the operator's telephone from the link circuit. The calling

sleeve supervisory relay CS, upon energizing, closes a circuit through the calling supervisory lamp CL and through ringing control relay RC, the latter circuit being traced from battery through the winding of the said control relay RC, normal contact 50 of relay GR, normal contact 47 of relay CT, and through alternate contact 48 of relay CS to ground. The ringing control relay RC, upon energizing, closes a circuit for the interrupter relay IR, traced from battery through the interrupter I, said relay IR, alternate contact 60 of relay RC, alternate contact 51 of relay AT and through alternate contact 61 of relay AS to ground. The relay IR, through the medium of the interrupter I, operates to intermittently connect ringing current from generator G to the terminals of the called subscriber's line.

Upon the response of the called subscriber, a series energizing circuit, including the calling tip relay CT and the impedance coil IC¹, is closed. The calling tip relay upon energizing, opens the circuit of the calling supervisory lamp CL and opens the circuit of the ringing control relay RC. The ringing control relay RC thereby deenergizes and opens the circuit of the interrupter relay IR at its contact 60. The two local subscribers may now carry on a conversation over the heavily marked conductors.

Assuming now that conversation has been terminated, the calling subscriber A, upon replacing his receiver, causes the answering supervisory lamp AL to glow in the same manner as hereinbefore described. The called subscriber, upon replacing his receiver, opens the circuit of the calling tip relay CT thereby permitting the said relay to deenergize and to close a circuit through the calling lamp CL. The operator, upon noting the glowing of the two supervisory lamps, removes the answering plug AP and calling plug CP from their respective jacks thereby permitting the apparatus to return to normal.

While I have described my invention operating in connection with a certain circuit arrangement, I do not wish to be limited to the same, as my invention can be adapted to operate in conjunction with other circuit arrangements and many changes and modifications will readily suggest themselves to those skilled in the art. Therefore, I do not wish to be limited to the exact structure shown, but aim to cover all such changes and modifications as come within the spirit and scope of the appended claims.

Having described my invention, what I claim as new and desire to secure by United States Letters Patent, is:

1. In a telephone system, a manual link circuit provided with automatic signaling apparatus, a relay associated with said link circuit for initiating the operation of said

- signaling apparatus, a called subscriber's line circuit, a trunk circuit, and means effective upon connection of said link circuit to said line circuit for operatively energizing said relay to initiate the operation of said signaling apparatus, said relay being ineffective upon the connection of said link circuit to said trunk circuit to operate said signaling apparatus.
- 10 2. In a telephone system, a manual link circuit provided with automatic signaling apparatus, a relay associated with said link circuit for initiating the operation of said signaling apparatus, a called subscriber's line circuit, a trunk circuit, means effective upon connection of said link circuit to said line circuit for operatively energizing said relay to initiate the operation of said signaling apparatus, said relay being ineffective upon the connection of said link circuit to said trunk circuit to operate said signaling apparatus, and a supervisory circuit controlled by said relay.
- 15 3. In a telephone system, a manual link circuit provided with automatic signaling apparatus, a relay associated with said link circuit for initiating the operation of said signaling apparatus, a called subscriber's line circuit, a trunk circuit, means effective upon connection of said link circuit to said line circuit for operatively energizing said relay to initiate the operation of said signaling apparatus said relay remaining inert upon the connection of said link circuit to said trunk circuit thereby preventing the operation of said signaling apparatus, and means associated with said trunk circuit for thereafter operating the said relay for controlling a supervisory circuit without affecting the said ringing apparatus.
- 20 4. In a telephone system, a manual link circuit provided with automatic signaling apparatus, a relay associated with said link circuit for initiating the operation of said signaling apparatus, a called subscriber's line circuit, a trunk circuit, means effective upon connection of said link circuit to said line circuit for operatively energizing said relay to initiate the operation of said signaling apparatus, said relay remaining inert upon the connection of said link circuit to said trunk circuit thereby preventing the operation of said signaling apparatus, and means associated with said trunk circuit for rendering said automatic ringing apparatus ineffective and for operating said relay for controlling the supervisory circuit.
- 25 5. In a telephone system, a manual link circuit provided with a calling supervisory signal, a relay connected to a talking strand of said link circuit for controlling said signal, a trunk circuit for connection to said link circuit for extending connection to a distant exchange, a called subscriber's line circuit adapted to be connected to said

trunk circuit, and means controlled by said called subscriber over the two sides of the said trunk circuit in multiple for actuating said relay to cause an operation of said supervisory signal.

6. In a telephone system, a manual link circuit provided with a calling supervisory signal, a relay connected to a talking conductor of said link circuit, a trunk circuit connected to said link circuit for extending a connection to a distant exchange, a called subscriber's line circuit connected to said trunk circuit, and means controlled by the called subscriber over the two sides of the said trunk circuit in parallel for operating said relay for controlling said supervisory circuit.

7. In a telephone system, a manual link circuit provided with a calling supervisory signal, a relay connected to a talking conductor of said link circuit, a trunk circuit connected to said link circuit for extending connections, a called subscriber's line circuit connected to said trunk circuit, and a simplex circuit including the two conductors of said trunk circuit for controlling a trunk circuit relay, means controlled by said trunk circuit relay for uniting the conductors of said link circuit thereby operating said first relay and actuating said signal, said simplex circuit being controlled by the called subscriber.

8. In a telephone system, a manual link circuit provided with a pair of talking conductors, a supervisory relay connected to one of said talking conductors, a trunk circuit connected to said link circuit, a called subscriber's line circuit connected to said trunk circuit, a simplex circuit including the two conductors of the said trunk circuit, means controlled by the called subscriber for increasing the current flowing in said simplex circuit, and means controlled by such increased flow for closing a bridge across said talking conductors to operate said supervisory relay.

9. In a telephone system the combination of a manual link circuit and a trunk circuit for extending connections between subscribers' lines, a pair of supervisory signals for said trunk circuit, means controlled by the connection of said link circuit to said trunk circuit for causing said supervisory signals to glow, means controlled by the connection of said trunk circuit to the called subscriber's line for effacing one of said signals, means controlled by the response of a called subscriber for effacing the other of said signals, means controlled by the disconnection of said trunk circuit from said called subscriber's line for again causing said first supervisory signal to glow, and means controlled by the disconnection of said link circuit from said trunk circuit for again effacing said last signal.

10. In a telephone system the combination of a manual link circuit and a trunk circuit for extending connections between subscribers' lines, a pair of supervisory signals for said trunk circuit, means controlled by the connection of said link circuit to said trunk circuit for causing said supervisory signals to glow, means controlled by the connection of said trunk circuit to the called subscriber's line for effacing one of said signals, means controlled by the response of a called subscriber for effacing the other of said signals, and means controlled by the disconnection of said trunk circuit from said called subscriber's line for again causing said first supervisory signal to glow.

11. In a telephone system the combination of a link circuit connected to a trunk circuit, of a called subscriber's line circuit connected to said trunk circuit, a pair of supervisory signals for said trunk circuit operative upon connection of said link circuit to said trunk circuit, means for effacing one of said signals upon the connection of said trunk circuit to the called subscriber's line, means controlled by the called subscriber for effacing the other of said signals, means for again causing said signals to glow, and operator and subscriber controlled means for again effacing said signals.

12. In a telephone system, a manual link circuit, a trunk circuit provided with a pair of supervisory signals, means responsive to the connection of said link circuit to said trunk circuit to cause said signals to glow, subscriber controlled means for effacing one of said signals, and operator controlled means for effacing the other of said signals.

13. In a telephone system, a manual link circuit provided with automatic signaling apparatus, a subscriber's line circuit, a trunk circuit for extending connections, means responsive to the connection of said manual link circuit to said subscriber's line circuit for rendering said signaling apparatus effective to signal the called substation, and means associated with said trunk circuit for preventing the operation of said automatic signaling apparatus when connection is established between said link circuit and said trunk circuit.

14. In a telephone system, a manual link circuit provided with automatic signaling apparatus, a called subscriber's line circuit, a trunk circuit extending to a distant exchange, means responsive to the connection of said manual link circuit to said subscriber's line circuit for initiating the operation of said automatic signaling apparatus, and apparatus associated with said trunk circuit for rendering said automatic signaling apparatus ineffective.

15. In a telephone system, a manual link circuit provided with automatic signaling apparatus, a called subscriber's line, a trunk

circuit, and electromagnetic means for said link circuit operative to actuate said ringing apparatus when the link circuit is connected to said called subscriber's line and for rendering ineffective said ringing apparatus when said link circuit is connected to said trunk circuit.

16. In a telephone system, a two-conductor link circuit, a supervisory relay connected to said link circuit, a trunk circuit, manual means for connecting said link circuit to said trunk circuit, apparatus associated with said trunk circuit and controllable over the two conductors thereof in parallel to unite said link circuit conductors to actuate said supervisory relay.

17. In a telephone system, a manual link circuit provided with automatic signaling apparatus, a called subscriber's line, a trunk circuit, electromagnetic means for said link circuit operative to actuate said ringing apparatus when the link circuit is connected to said called subscriber's line and for rendering ineffective said ringing apparatus when said link circuit is connected to said trunk circuit, and a supervisory signal for said link circuit operable either over said called line or over said trunk circuit.

18. In a telephone system, a two-conductor link circuit, a supervisory relay connected to said link circuit, a trunk circuit, manual means for connecting said link circuit to said trunk circuit, apparatus associated with said trunk circuit and controllable over the two conductors thereof in parallel to unite said link circuit conductors to actuate said supervisory relay and subscriber controlled means for controlling said parallel circuit.

19. In a telephone system, the combination of a link circuit connected to a trunk circuit, of a calling subscriber's line circuit connected to said trunk circuit, a pair of supervisory signals for said trunk circuit, means controlled by the connection of said link circuit to said trunk circuit for operating said supervisory signals, means responsive to the connection of said trunk circuit to said called subscriber's line circuit to efface one of said signals, and means responsive to the response of the called subscriber for effacing the other of said signals.

20. In a telephone system, a subscriber's line, a link circuit, a trunk circuit, a pair of signals for said trunk circuit, means responsive to the connection of said link circuit to said trunk circuit to operate said signals, means responsive to the connection of said trunk circuit to said subscriber's line to efface one of said signals, and subscriber controlled means for effacing the other of said signals.

21. In a telephone system, a subscriber's line, a link circuit, a trunk circuit, supervisory signals for said trunk circuit, circuits

- for said supervisory signals closed responsive to the connection of said link circuit to said trunk circuit, means for opening one of said circuits responsive to connection of 5 said trunk circuit to said subscriber's line, means controlled by said subscriber to open and close the other of said circuits, and means controlled by the disconnection of said link circuit from said trunk circuit to 10 again close said first circuit.
22. In a telephone system, a subscriber's line circuit, a link circuit, a trunk circuit, a supervisory signal for said link circuit, means controlled over said line circuit when 15 said link circuit is connected directly to said line circuit to operate said signal, and means controlled over the two sides of the trunk circuit in parallel to operate said signal when said link circuit is connected to said 20 trunk circuit.
23. A telephone system including a manual link circuit provided with a pair of talking conductors, a calling line connected to said link circuit, a calling supervisory signal, a relay connected to one of said talking conductors for controlling said signal, a trunk circuit, manual means for connecting said trunk circuit to said link circuit to extend a connection therefrom, a called subscriber's line connected to the opposite end 25 of said trunk circuit, a simplex circuit in-

cluding said trunk circuit, means for producing a change in said simplex circuit to operate said link circuit relay to thereby actuate said signal, and central office means 35 for supplying both said calling line and said called line with talking current.

24. A telephone system including a manual link circuit provided with ringing means, a called subscriber's line, a trunk 40 circuit, means responsive to the connection of said link circuit to said called subscriber's line to actuate said ringing means, and means associated with said trunk circuit to prevent the operation of said ringing means 45 when said link circuit is connected to said trunk circuit.

25. A telephone system including a manual link circuit, ringing means associated with said link circuit, a subscriber's line circuit, a trunk circuit, and means for said link circuit operative only when said link circuit is connected to said subscriber's line for initiating the operation of said ringing means. 55

Signed by me at Chicago, in the county of Cook and State of Illinois, in the presence of two witnesses.
